US00D591590S

(12) **United States Design Patent**
Wilson et al.

(10) **Patent No.:** US D591,590 S
(45) **Date of Patent:** ** May 5, 2009

(54) **CONTAINER**

(75) Inventors: **Michael J. Wilson**, Rossmoor, CA (US);
Bryan W. Ware, Pleasanton, CA (US);
Sean C. Silk, Los Angeles, CA (US)

(73) Assignee: **MARS, Incorporated**, McLean, VA
(US)

(**) Term: **14 Years**

(21) Appl. No.: **29/321,733**

(22) Filed: **Jul. 22, 2008**

Related U.S. Application Data

(63) Continuation of application No. 29/298,079, filed on Nov. 28, 2007, now abandoned.

(51) **LOC (9) Cl.** 09-03

(52) **U.S. Cl.** D9/428
